UNITED STATES PATENT OFFICE.

GUY B. WAITE, OF NEW YORK, N. Y.

CORE BOX FOR CONCRETE FLOORS.

Application filed December 9, 1921. Serial No. 521,091.

To all whom it may concern:

Be it known that I, GUY B. WAITE, citizen of the United States, residing at New York, in the borough of Manhattan and State of New York, have invented certain new and useful Improvements in Core Boxes for Concrete Floors, of which the following is a specification.

This invention relates to improvements in core-boxes for concrete floors and particularly of the type which permanently remain in the finished floors to form hollow spaces to lessen the weight of the floors having long spans and which must be of considerable thickness to sustain the loads.

Various methods have been resorted to in forming hollows in the central parts of the floors, or those parts which have little value in thick floors, and on account of specialized labor demanded in building constructions, it has been found that the present methods are very expensive.

This invention is for the purpose of avoiding the use of several kinds of expensive labor, by constructing the core-boxes in a manner which will permit the molding of the ceiling on the underside of the floor at the same time the floor and beams above are being formed, or in other words, forming the floor, beams and ceiling in one general operation.

The objects of this invention are attained by the means illustrated in the accompanying drawing, in which:—

Fig. 1 is a view in vertical cross-section of a portion of a floor of a certain construction. Fig. 2 is a horizontal sectional view of the form of floor shown in Fig. 1. Fig. 3 is a detail perspective view of one of the core-boxes. Fig. 4 is a vertical cross-sectional view of a modified form of the floor. Fig. 5 is a view similar to Fig. 4, showing a further modified form of floor. Fig. 6, is a horizontal cross-section of one of the core-boxes. Fig. 7, is a detail sectional view of one corner of a core-box. Fig. 8 is a detail view showing a modified form of supporting foot, and Fig. 9 is a view showing a modified form of core-box.

Similar reference numerals in all of the figures of the drawing designate like parts.

This improved core-box is adapted to be used in either one-way or two-way floors, that is, either having the beams all running in one direction only, or running in both directions across the span. In the

drawing is illustrated the two-way construction, excepting Figure 9, which shows one end of a core-box for use in one-way floors.

The core-boxes are preferably constructed of metal, and for the two-way floor are formed rectangular in cross-section having the four vertical sides 10, the top edges of which are turned outwardly to form the top-flanges 11, and whose lower edges are bent inwardly to form the bottom flanges 12, said bottom-flanges being shorter than the length of the sides, so that the sides of the boxes at the corners can be extended to a point below the bottom-flanges to form feet 13 which are preferably pointed to engage in the wooden centering which is primarily erected to support the forms and the floor while it is being formed. The pointed feet can be formed integral with the sides of the box and formed with double points as shown in Fig. 3, or they can be formed integral with the sides and with a single point, as shown in Fig. 7, or they can be formed separately from the sides of the box and be riveted in place, as shown in Fig. 8, of the drawing. Between the feet and beneath the bottom flanges are formed the openings or open spaces 14, which are adapted to permit the concrete to ooze under the bottom flanges to form the ceiling portion of the floor which lies beneath the core-boxes. The bottom-flanges form reinforcing ribs for the bottom edges of the sides, and the top-flanges form reinforcing ribs for the top edges and also a suitable support for a cover 15, which might be of concrete, as shown in Figs. 1 and 4, or may be of metal or other flat material, as shown at 16 in Fig. 5.

The sides of the core-boxes are preferably corrugated adjacent the corners, as shown at 17, and the corrugations are preferably deeper at their lower ends, so that the pleats thus formed will give a taper to the boxes which will permit them to be nested one within the other for shipping purposes and practically form rectangular supporting legs of the corners extending substantially the full height of the boxes. It is further contemplated to use reinforcing wires 18, which are preferably connected to the feet of the boxes below the bottom flanges 12, so that, when the ceiling is formed, these wires will be imbedded therein.

The top and bottom-flanges, the vertical corrugations, and the wires 18, permit the

use of relatively light weight material from which the boxes can be formed, and where the material used is extra light weight, the separately made feet are desirable.

- 5 In constructing a floor, the centering 19 is first erected as is done in other systems, then the core-boxes are placed in position. These boxes stand up from the centering far enough to permit the concrete to ooze beneath the bottom-flanges, and the tops of the boxes are preferably left open or uncovered, so that when necessary some of the concrete material can be poured on the interior of the boxes to be sure the ceiling portion 15 within the area of the boxes is of sufficient thickness. After the ceiling portion has been poured, then the tops or covers 15 can be placed in position, and then the ribs or beams of the floor are poured to complete 20 the floor. The tops or covers 15 are preferably formed with a depending portion on their undersides which is adapted to enter slightly into the box to brace the box and also to retain the cover in position, especially when the concrete is being poured. If the covers 15 are of sufficient thickness, the concrete in the beams need only be poured to the top surfaces of the covers, as shown on Fig. 1, but should the covers 30 be relatively thin, whether of concrete or other material, then the concrete is poured over the covers to a sufficient thickness to form a floor thick enough to support the stresses, as shown in Figs. 4 and 5.
- 35 As shown in Fig. 5, where a thin metal cover is used, the top edges of the boxes are bent to form pockets 21 to receive the covers and to prevent their accidental displacement.
- 40 It is understood, that when the boxes are positioned upon the bare centering planks, the teeth at the bottom of the feet are caused to slightly enter the material of the centering to positively position them and hold them in position while the concrete is being poured or inserted.

Having thus fully described the invention, what is claimed is:—

1. A core-box for concrete floor constructions adapted to be embedded and remain in the floor, said box being formed with inclined sides having top-flanges bent outwardly to permit nesting of the boxes during shipment, and bottom-flanges bent

inwardly, and legs provided with teeth at 55 their lower edges to retain the boxes in position upon temporary centering while the concrete is being poured.

2. A core-box for concrete floor constructions adapted to be embedded and remain in the floor, said box being formed open at the top and bottom and having horizontal reinforcing flanges at both the top and bottom edges, the top flange extending outwardly from the box, a detachable cover for the open top having a depending portion to extend slightly into the top of the box, penetrating means at the lower edges of the box which will support the bottom edges above the temporary centering used during construction and bite into the centering to retain the box in position while the concrete is being poured.

3. A core-box for concrete floor constructions adapted to be embedded and remain in the floor, said box having an open top and bottom and reinforced legs at the corners formed by inwardly extending pleats adjacent the corners, said pleats being tapered downwardly and inwardly to 80 also taper the box, a detachable cover for the open top, penetrating means at the lower ends of the legs to support the bottom edges of the box above the temporary centering used during construction and to 85 positively retain the box in position on the centering while the concrete is being poured.

4. A core-box for concrete floor constructions adapted to be embedded and remain in the floor, said box having an open top and bottom provided with pleats adjacent the corners to form the box tapered with reinforcing legs at the corners, said legs having pointed ends projecting below 95 the bottom edges of the box, a detachable cover for the open top, reinforcing wires extending from side to side of the box below the bottom edges thereof, said pointed ends adapted to support the bottom edges 100 of the box above the temporary centering used during construction and positively retain the box in position on the centering while the floor is being constructed.

In testimony whereof I affix my signature.

GUY B. WAITE.
